5/234

5679

The figure on the drawing is a face view of a font of electroluminescent characters illustrating my new design and showing the basic character together with the numerals formed therefrom.

I claim:

The ornamental design for a font of electroluminescent characters, as shown and described.

UNITED STATES PATENT OFFICE
CERTIFICATE OF CORRECTION

Patent No. Des. No. 227,602 Dated July 3, 1973

Inventor(s) Brian Astle

It is certified that error appears in the above-identified patent and that said Letters Patent are hereby corrected as shown below:

In the title, change "Electroluminescent" to read

-- Electro-optical --. Column 1, line 2, "electroluminescent"
should read -- electro-optical --.

Signed and sealed this 14th day of January 1975.
